UNITED STATES PATENT OFFICE

172,398

SHOE OR SIMILAR ARTICLE

Roy Maling, Chestnut Hill, Mass.

Application March 29, 1952, Serial No. 19,115

Term of patent 14 years

(Cl. D7—5)

To all whom it may concern:

Be it known that I, Roy Maling, a citizen of the United States, residing in Chesnut Hill, in the county of Middlesex and State of Massachusetts, have invented a new, original, and ornamental Design for a Shoe or Similar Article, of which the following is a specification, reference being had to the accompanying drawing, forming part thereof.

In the drawing:

Fig. 1 is a side elevation of a shoe showing my new design, both sides of the shoe being substantially the same;

Fig. 2 is a bottom plan view thereof; and

Fig. 3 is a rear elevation thereof.

The characteristic features of my new design are shown in full lines.

I claim:

The ornamental design for a shoe or similar article, substantially as shown and described.
